UNITED STATES PATENT OFFICE.

EDWARD J. NYE, JR., OF DOLLAR BAY, MICHIGAN.

COPPER-BILLET MOLD.

1,250,212.

Specification of Letters Patent. Patented Dec. 18, 1917.

Application filed April 3, 1917. Serial No. 159,477.

To all whom it may concern:

Be it known that I, EDWARD J. NYE, Jr., a citizen of the United States, residing at Dollar Bay, in the county of Houghton and 5 State of Michigan, have invented certain new and useful Improvements in Copper-Billet Molds; and I do hereby declare the following to be a full, clear, and exact description of the invention, such as will enable 10 others skilled in the art to which it appertains to make and use the same.

The invention relates to improvements in copper billet molds.

The object of the present invention is to 15 improve the construction of copper billet molds and to provide a simple, practical and efficient mold designed for molding copper bars or billets and capable of enabling the same to be molded of a considerable length 20 without liability of the copper splashing in the bottom of the mold and against the sides thereof and producing what is known as a cold set piece of copper which cannot be used in the manufacture of copper requiring 25 the rolling or drawing of the metal.

A further object of the invention is to provide a copper billet mold of this character adapted to permit the molten copper to be poured into the mold while the same is in a 30 horizontal position and without splashing and capable of being brought gradually into an upright position.

With these and other objects in view, the invention consists in the construction and 35 novel combination of parts hereinafter fully described, illustrated in the accompanying drawings and pointed out in the claims here-to appended; it being understood that various changes in the form, proportion, size 40 and minor details of construction, within the scope of the claims, may be resorted to without departing from the spirit or sacrificing any of the advantages of the invention.

In the drawings:

45 Figure 1 is a side elevation of a copper billet mold constructed in accordance with this invention.

Fig. 2 is a plan view of the same.

Fig. 3 is a longitudinal sectional view of 50 the copper billet mold.

Fig. 4 is a transverse sectional view of the same.

Fig. 5 is an end elevation, the end gate or 55 wall being removed.

Fig. 6 is a detail perspective view of the end wall showing the inner face thereof.

Like numerals of reference designate corresponding parts in the several figures of the drawings.

In the accompanying drawings, in which 60 is illustrated the preferred embodiment of the invention, the copper billet mold, which may be made of various sizes for molding round billets or rods or bars, consists of a cylindrical body portion 1 provided at one 65 end with an end wall 2 and having a semi-cylindrical extension 3 at the other end 4, which is open and which is preferably beveled or tapered at the inner end of the semi-cylindrical extension. The cylindrical 70 body of the mold is provided at opposite sides with trunnions 5, which are adapted to be mounted in suitable bearings 6 of a stand or support 7, which may be of any desired character. The mold may be constructed of 75 copper, cast iron or other suitable material and when made of copper will be provided with relatively thick walls so that there may be no liability of the copper bending when pulling or otherwise removing the billets 80 from the mold. The trunnions may be cast 85 integral with the mold or consist of pins cast in the metal of the mold and are preferably of steel when the mold is constructed of copper.

The end wall 2 is provided with a central opening 8 receiving a removable tapered plug 9 forming a closure for the opening and projecting beyond the end wall 2. The projecting plug forms a stop, as hereinafter 90 explained, and it is removable to facilitate the removal of the billet from the mold when necessary.

The semi-cylindrical extension is provided at the outer end with a removable segmental 95 wall or gate 10 of semi-circular shape having its inner face recessed at 11 adjacent to the periphery of the end wall or gate and forming a projecting segmental portion 12 to fit in a groove 13 in the outer end of the 100 extension 3, which constitutes a feed trough when the mold is in a horizontal position. The end wall 10 is provided at opposite sides with integral lugs 14 projecting laterally from the outer end of the extension 105 and adapted to be engaged by hooks 15 provided at the inner ends of shanks with loops 16 which are arranged on lugs 17 preferably formed integral with or cast into the metal of the mold. The end 10 is 110 adapted to be removed after the metal has been poured and the mold is arranged in an

upright position and it will permit the billet to be extracted from the mold.

The mold is provided at its interior with an indicating mark 18 designed to serve as 5 a guide for pouring the metal to the proper elevation for making a billet or bar of copper of the desired length.

The pin 9, which projects from the end wall 2, to form a lug or stud, is adapted to 10 engage a stop 20 of a frame 21 for limiting the upward movement of the bottom end of the mold so that the mold will occupy a horizontal position when the same is arranged for pouring the metal into the extension. The mold is provided adjacent to 15 its end 2 with a projecting eye 22 adapted to receive one end of a hoisting rope or cable 23 arranged on an overhead pulley 24 and designed to be connected with any suitable operating device. It is necessary to 20 gradually lower the body portion of the mold to prevent any splash which is eliminated by the pouring of the metal into the mold at the extension or trough, and while 25 a simple hoisting rope or cable and an overhead pulley are shown to illustrate one means of accomplishing this result, it will be apparent that various other devices may be used for enabling the mold to be brought 30 from a horizontal position to an upright position either manually or mechanically to secure the desired degree of steadiness and at the same time effect a movement of the required speed. The frame and the stand 35 are shown separate in the accompanying drawings, but the parts may be mounted in any desired manner, as will be readily understood.

What is claimed is:

40 1. A device of the class described including a stand, a mold comprising a body portion open at one end and a longitudinal trough extending from the open end of the body, said mold being pivotally mounted 45 intermediate of its ends and supported by the stand, a removable closure for the outer end of the trough, and hoisting mechanism

connected with the body of the mold for swinging the same from a vertical to a horizontal position. 50

2. A copper billet mold including a cylindrical body closed at one end and pivotally mounted at the other end and provided at the pivoted end with a longitudinal semi-cylindrical extension adapted to form a 55 trough when the body is in a horizontal position, a removable segmental closure for the outer end of the extension, said closure being provided at opposite sides with lugs, and hooks pivotally mounted on the extension 60 at opposite sides thereof and arranged to swing into and out of engagement with the said lugs.

3. A device of the class described including a stand having bearings, a substantially 65 cylindrical mold comprising a body closed at one end and open at the other end and provided at opposite sides thereof with trunnions arranged in the said bearings, said body being provided at its open end with a 70 longitudinally disposed approximately semi-cylindrical extension having a removable end closure, and hoisting mechanism connected with the body of the mold at the closed end thereof for swinging the mold from a vertical to a horizontal position. 75

4. A device of the class described including a pivotally mounted mold open at one end and closed at the other and provided at the closed end with an aperture and having a plug projecting therefrom, said mold being provided at the open end with an extension forming a trough when the mold is in a horizontal position, hoisting mechanism connected with the closed end of the mold, 80 and a stop located in the path of the projecting portion of the plug. 85

In testimony whereof I affix my signature in presence of two witnesses.

EDWARD J. NYE, JR.
